(Cl. D52—10)

FIG. 1 is a perspective view of the analytical balance unit showing our new design, as viewed from the left front.

FIG. 2 is a view of the article as seen in rear elevation, with portions of the conventional cord broken away for convenience of illustration,

FIG. 3 is a perspective view of the article taken diametrically opposite to FIG. 1, with the cord portion fragmentarily shown for convenience of illustration, and

FIG. 4 is a front elevational view of the article.

The undisclosed, right-hand side of the article is substantially identical with the left-hand side shown in FIG. 1 except for omission of a lever from the disclosed operating knob.

We claim:
The ornamental design for an analytical balance unit, as shown and described.
